CHILD'S STOOL OR THE LIKE

Theodore T. Michals, 350 Fairbank Road,
Riverside, Ill. 60546

Filed Aug. 5, 1965, Ser. No. 86,454

Term of patent 14 years

(Cl. D15—8)

The figure is a perspective view of a child's stool or the like showing my new design.

The side of the stool is the same in appearance throughout its periphery.

I claim:

The ornamental design for a child's stool or the like, as shown and described.
